A. E. BROWN

DENTAL ARTICULATOR

Filed Oct. 23, 1926

Fig. 2.

inventor;
Archie E. Brown
Vernon C. Hodges
By *his Atty.*

UNITED STATES PATENT OFFICE.

ARCHIE EDWARDS BROWN, OF EL PASO, TEXAS.

DENTAL ARTICULATOR.

Application filed October 23, 1926. Serial No. 143,647.

This invention relates to an improvement in dental articulators.

The object of the invention is to provide a device of this character which may be used by dentists in making and setting up artificial teeth to enable them to accomplish that purpose with greater ease and better results.

A further object of the invention is to permit the dentist to correct a mistake which he finds that he has made, after he has set teeth on the wax and tried them in the mouth.

With these objects in view, the invention is constructed of supporting plates or holders for the plaster cast of the gums, one of which plates has a post mounted thereon, which telescopically receives a barrel to which a lever is pivotally connected, and which lever supports the other plate through the medium of a ball and socket joint. The pivot-pin for the lever is spring-pressed and mounted in a slot so as to permit movement of the upper plate relative to the lower one.

The lever supports a barrel provided with a slotted outer end formed into a socket which receives a ball connected with the upper plate to provide a ball and socket joint between the supporting lever and said upper plate, in order to enable the dentist to move one of the casts relative to the other.

In the accompanying drawings:

Fig. 1 is a perspective view of the complete invention with a portion broken away;

Fig. 2 is a side elevation partly in section of the lower plate and post mounted thereon.

In the drawings, the numerals 1 and 2 indicate the lower and upper plates respectively which hold the plaster casts of the upper and lower gums. The plate 1 has a post 3 mounted on the rear end thereof, which telescopically receives a barrel 4 thereover. A supporting-screw 5 extends through post 3 and carries the barrel 4 on the upper end thereof, and this screw 5 may be adjusted and extended upwardly from the post 3, so as to adjust the position of the barrel 4 thereon. The post 3 is provided with a groove 6, which receives a set-screw 7 for holding the barrel 4 in position on the post.

The barrel 4 terminates in a plate 8 provided with a groove 9 therein, which receives the pivot-pin 10 for a lever 11. This lever 11 is provided with a bifurcated end 12 which receives the plate 8 as clearly shown in Fig. 1. A spring 13 is positioned in the

groove 9, and is interposed between the pivot pin 10 and a plate 14 secured by screws 15 to the face of the plate 8, in order to hold the pivot-pin 10 and the lever 11 in their forward position, but to permit them to be moved back for arranging the teeth in the plaster casts. A lug 16 extends laterally from the barrel 4, and receives a set-screw 17 which extends beneath and supports the lever 11.

A barrel 18 is telescopically mounted on the lever 11 and held in position thereon by a set-screw 19 extending into a groove 20 in the lever 11. The barrel 18 is slotted as at 21 to form a socket 22 in the forward end thereof for receiving and embracing a ball 23 made integral with, and extending downwardly from, the plate 2. The barrel 18 is threaded, as at 24, to receive a threaded ring 25, which may be screwed forwardly thereon to close the slit 21, and to secure the socket 22 over the ball 23 in order to provide a supporting action between these members.

In use, the plaster casts of the upper and lower gums are secured on the plates 1 and 2, which may be adjusted relative to each other by the adjustment of the barrel 4 on the post 3, and also by the movement of the plate 2 relative to the plate 1 in the ball and socket joint. The pivotal connection between the lever 11 and the plate 8 allows the upper supporting lever to open and rest at an angle of approximately 45°. The movement of the pivotal pin 10 in the groove 9 enables the dentist to move the upper plate back and forth relative to the lower one when necessary in arranging the teeth of the cast. The universal joints 22 and 23 enables the dentist to correct a mistake which he finds he has made after he has set the teeth upon the wax and tried them in the mouth.

I claim:

1. A device of the character described including a lower plate, a post mounted thereon, a barrel fitted over said post, means extending upwardly from the end of the post, and adjustably supporting the barrel thereon, a lever pivotally mounted upon the barrel, and an upper plate supported by said lever.

2. A device of the character described including a lower supporting plate, a post mounted thereon, a barrel fitted over said post and terminating in a plate, a supporting screw extending upwardly from the post and adjustably supporting the barrel there-

on, means for holding the barrel in its adjusted position, said last-mentioned plate having a groove formed therein, a lever having a bifurcated end fitted over said plate and having a pivot pin extending in the groove, a spring for resiliently holding the pivot-pin in its forward position in the groove, and an upper supporting plate carried by said lever.

3. A device of the character described including a lower supporting plate, a post mounted thereon, a barrel fitted over said post and terminating in a plate, a supporting screw extending upwardly from the post and adjustably supporting the barrel thereon, means for holding the barrel in its adjusted position, said last-mentioned plate having a groove formed therein, a lever having a bifurcated end fitted over said plate and having a pivot pin extending in the groove, a spring for resiliently holding the pivot-pin in its forward position in the groove, a barrel telescopically mounted on the lever, and having a slotted outer end forming a supporting socket, an upper supporting plate having a ball-member received in, and supported from, said socket, and means for clamping the socket over the ball.

4. A device of the character described including a plate, a post mounted thereon, a barrel fitted over said post and terminating

in a plate having a groove formed therein, a lever having a bifurcated end fitted over said plate and having a pivot pin extending in the groove, a spring for resiliently holding the pivot pin in its forward position in the groove, and an upper plate connected with the lever.

5. A device of the character described including a lower supporting plate, a lever pivotally mounted thereon, a barrel telescopically mounted on said lever, said barrel having the outer end thereof slotted, a socket formed in the extreme end of said barrel, an upper supporting plate having a ball connected therewith and received in said socket, said barrel having screw threads formed thereon about the slotted portion thereof, and a nut screwed on said threads for clamping the slotted socket on the ball.

6. A device of the character described including supporting members, supporting means for adjustably connecting said members together, including a plate having a groove therein, a lever connected with one of the plates and having a pivot pin extending in the groove, and a spring interposed between one end of the groove and the pivot pin for resiliently holding the pivot pin in proper position in the groove.

In testimony whereof I affix my signature.
ARCHIE EDWARDS BROWN.
